UNITED STATES PATENT OFFICE.

CLYDE C. MANCHESTER, OF TOLEDO, OHIO, ASSIGNOR TO INDUSTRIAL RESEARCH CORPORATION, OF TOLEDO, OHIO, A CORPORATION OF DELAWARE.

AIR CLEANER.

Application filed February 21, 1920, Serial No. 360,507. Renewed September 10, 1926.

This invention relates to improvements in air cleaners. While it is intended particularly for use in connection with internal combustion engines for removing the dust and dirt from the air entering the carburetor, it is nevertheless also useful for cleaning air for other purposes.

The principal object of the invention is the provision of means for the purpose specified, which shall be economical to manufacture and efficient in operation.

Another object of the invention is the provision of a dust box having a large dust holding capacity, which may be easily and quickly removed and which is provided with several compartments in order to prevent the undue accumulation of dust in one portion of the box as might occur under certain circumstances of operation.

Another object of the invention is the combination with a heated elongated surface of an internal combustion engine, such as the cylinder block or the exhaust pipe, of an air cleaner having an elongated slot through which the air must enter the cleaner, the cleaner being positioned with the slot side adjacent to said heated surface, whereby the entering air is not only heated, thus assisting in the process of carburetion, but also the air taken into the device comes from between the cleaner and the engine, where the dust content is less than upon the side of the cleaner remote from the engine, that is, in cases where the engine is mounted upon a tractor or other vehicle.

Other objects will appear as I proceed with the description of that embodiment of the invention, which, for the purposes of the present application I have illustrated in the accompanying drawings, in which,

Figure I is a view partly in central longitudinal section of a cleaner embodying my invention.

Fig. II is a transverse section taken substantially on the line II-II, Fig. I.

Fig. III is a longitudinal section taken substantially on the line III-III, Fig. II.

Fig. IV is a fragmental end view of an internal combustion engine showing my cleaner so arranged with respect thereto as to take air from between the cleaner and engine exclusively and to compel the air en-

tering the cleaner to pass over a heated surface.

Fig. V is a view similar to Fig. IV but showing a deflecting plate added to the cleaner in order to accentuate the air heating effect.

The air offtake pipe through which the clean air leaves the apparatus is indicated by the numeral 10. When the cleaner is used in connection with an internal combustion engine, this pipe is attached to the air intake of the carburetor as shown in Fig. IV. When the cleaner is used for other purposes, the pipe may be attached to any suction creating means, or in case the air to be cleaned is forced through the cleaner rather than drawn through by suction, the pipe 10 may constitute simply a clean air discharge outlet. As illustrated in the drawings, this pipe is the support from which the cleaner proper is hung. The latter consists in general of a dust separating chamber 11 and a dust box 12. The separating chamber is made up of two parallel end pieces 13 joined by a rectangular sheet metal element bent into a convolute or helical wall 14, with spaced overlapping portions 15 and 16 upon the upper side thereof. The off-take pipe 10 extends through openings in these overlapping portions, and terminates preferably flush with the lower one. The joints between the pipe 10 and the overlapping portions 15 and 16 are air tight and strong enough to support the weight of the cleaner with the dust box filled.

A baffle plate 17 extends from end to end of the separating chamber, and is positioned at one longitudinal edge adjacent the lower wall 15 of the overlapping portions. In a transverse direction this baffle plate is curved so as to bring the opposite longitudinal edge some distance inwardly from the wall 15. A baffle 18 similar in shape to the baffle 17 and also extending from end to end of the separating chamber is mounted with one longitudinal edge resting against and preferably secured to the lower wall of the chamber the opposite edge being spaced from the wall. This lower wall has one or more perforations 19 throughout its length on one side of the baffle 18 and one or more perforations 20 therebeneath.

On the under side of the under wall of the separating chamber are guides 21 extending for the full length of the chamber. The dust box 12 is made up of end pieces 22 joined by 5 a curved body portion 23 with outwardly flaring edges adapted to run in the guides 21. At intervals throughout the length of the dust box are partitions 24 dividing the box into compartments, the number of which may be 10 varied to suit different conditions.

In operation, my invention depends for its cleaning action upon centrifugal force assisted by gravity. The dirty air entering through the slot between wall 15 and the 15 edge of wall 16, is given a rapid circulatory motion around a horizontal axis, and by reason of this movement the dirt particles, which are heavier than air, are thrown to the outside against the wall of the chamber, and 20 are carried along by the movement of the air and by the force of gravity until they drop through the hole or holes 19 to the dust box 12, the clean air passing on in a whirl but being deflected slightly toward the middle 25 of the chamber by the baffle 18. If any dirt remains in the air after leaving the upper edge of baffle 18, and is then thrown outward against wall 14, it thereafter descends along that wall by force of gravity 30 and passes through the opening or openings 20 into the dust box. The air continuing its whirl strikes baffle 17 and is again deflected inwardly, after which a part of it, particularly the dirty part, may continue its 35 rotation. The clean air, however, being acted upon by the suction through pipe 10 makes a sudden turn around the lower edge of the baffle 17 and passes thence into the pipe 10. This sudden turn also has a cleaning 40 effect, as the momentum of any heavy dirt particles will tend to cause them to continue in the direction in which they are moving, and thus they are separated out and eventually collect on one side or the other of 45 the chamber wall, and descend along said wall to the dust box. The latter may be removed at intervals by sliding it longitudinally out of the guides 21 and may then be emptied. Partitions 24 serve to prevent piling 50 up of dust in one end of the box when the device is tilted endwise as might happen where it is used upon a tractor or other vehicle.

In Figs. IV and V, I have illustrated a 55 mode of application of my cleaner to a gas engine, such that certain beneficial results may be obtained which are not inherent in cleaners generally. In Fig. IV the cleaner is identical with that shown and described in 60 the preceding figures, but it is here supported upon the engine block in such manner as to bring the air inlet side of the cleaner towards the engine with the air inlet itself at the upper side edge of the engine exhaust pipe 25, 65 the edge of the overlapping portion 16 of

the upper part of the cleaner bearing against the exhaust pipe so that all of the air entering the cleaner must pass up over the surface of the exhaust pipe and become heated thereby. Thus, not only is the air entering 70 the cleaner heated, but furthermore, it is taken altogether from that side of the cleaner which is towards the engine. Hence, when the cleaner is mounted upon a tractor or road vehicle, the air intake slot is as far away 75 from the road wheel on that side of the machine as it is possible to have it, and the dust which is stirred up by the wheel is less dense there than it would be upon the side of the cleaner remote from the engine. 80

In Fig. IV, I have shown the air offtake pipe 10 as passing up over the engine block, and down the other side to the carburetor 26, but this is by way of illustration only 85 as it will be readily understood that the carburetor may be located upon the same side as the exhaust pipe and air cleaner if desired. Furthermore I desire it to be understood that any heated surface of a length at least equal to the length of the cleaner will 90 answer the purpose of heating the air, and hence the cleaner may be placed adjacent such other heated surface if it is convenient or undesirable to mount the cleaner near the exhaust pipe. 95

In Fig. V is shown a slight modification where an additional deflecting plate 27 of the same length as the cleaner is secured to the side thereof, and is curved or bent so as to provide an air passage of constant 100 size around a considerable portion of the exhaust pipe 25 or other heated surface. The shape of the plate 27 is of course dependent upon the shape of the heated surface with which it is to be used. 105

I claim as my invention:

1. In an air cleaner, a separating chamber substantially helical in cross section with its axis horizontal, whereby spaced overlapping walls are provided upon the upper side of 110 the chamber, an air offtake pipe extending through said overlapping walls, said chamber having a dust exit opening along the lower portion thereof, and a dust box depending from said chamber around said opening. 115

2. In an air cleaner, a separating chamber substantially helical in cross section with its axis horizontal, whereby spaced overlapping walls are provided upon the upper side of 120 the chamber, an air offtake pipe extending through said overlapping walls, a baffle plate mounted below the lower end of said offtake pipe, said chamber having a dust exit opening along the lower portion thereof, and a dust box depending from said chamber around said opening. 125

3. In an air cleaner, a separating chamber substantially helical in cross section with its axis horizontal, whereby spaced overlapping 130

walls are provided upon the upper side of the chamber, an air offtake pipe extending through said overlapping walls, and terminating substantially flush with the lower one, a baffle plate curved in cross section mounted below said offtake pipe with one longitudinal edge adjacent the chamber wall upon the side of the offtake pipe which is nearest the entrance of the air passage, the other edge being spaced from said wall, said chamber having a dust exit opening along the lower portion thereof, and a dust box depending from said chamber around said opening.

4. In an air cleaner, a separating chamber substantially helical in cross section with its axis horizontal, whereby spaced overlapping walls are provided upon the upper side of the chamber, an air offtake pipe extending through said overlapping walls, and terminating substantially flush with the lower one, a baffle plate extending from end to end of said chamber, and curved in cross section mounted below said offtake pipe with one longitudinal edge adjacent the chamber wall upon the side of the offtake pipe which is nearest the entrance of the air passage and the other edge spaced from said wall, said chamber having a dust exit opening along the lower portion thereof, and a dust box depending from said chamber around said opening.

5. In an air cleaner, a separating chamber substantially helical in cross section with its axis horizontal, whereby spaced overlapping walls are provided upon the upper side of the chamber, an air offtake pipe, extending through said overlapping walls, said chamber having dust exit openings at the bottom throughout its entire length, longitudinal guides upon said chamber on opposite sides of the openings and a dust box substantially equal in length to the separating chamber, slideable in said guides into and out of position.

6. In an air cleaner, a separating chamber substantially helical in cross section whereby spaced overlapping walls are provided above the upper side of the chamber; an air off-take pipe extending through said overlapping walls; and means for removing dust from said chamber.

7. In an air cleaner, a separating chamber, an air offtake pipe leading therefrom, said chamber having an air inlet passage arranged to cause the air to partake of a whirling motion about a horizontal axis, the lower wall having an imperforate portion extending from end to end, and having an opening on each side thereof, a dust box depending from the chamber enclosing said openings, and a transversely curved baffle plate attached at one longitudinal edge to the imperforate portion, and spaced from the wall at its opposite edge, said plate

covering the opening farthest from the air entrance in the path taken by the air.

8. The combination with an internal combustion engine having a heated surface extending for a substantial distance in one direction horizontally, of an air cleaner having a horizontally arranged intake slot positioned adjacent said heated surface and a deflecting plate positioned adjacent and co-extensive with the lower wall of said slot. 70

9. The combination with an internal combustion engine having a heated surface extending for a substantial distance in one direction horizontally, of an air cleaner having a horizontally arranged intake slot on 80 one side a substantial distance above the bottom thereof, said cleaner being positioned so as to bring said intake slot adjacent the heated surface above the bottom thereof, whereby the air entering the cleaner moves upwardly between it and the heated surface and a deflecting plate positioned adjacent and co-extensive with the lower wall of said slot. 85

10. In combination with an internal combustion engine having a heated surface extending for a substantial distance in one direction horizontally, of an air cleaner having a horizontally arranged intake slot positioned adjacent said heated surface, and a deflecting plate of a length substantially equal to that of the cleaner attached at its upper edge to the side of the cleaner below said slot, and bent substantially concentric with said heated surface whereby the air entering said slot is caused first to pass over a considerable portion of said heated surface. 90

11. In combination with an internal combustion engine having a side surface extending for a substantial distance in one direction horizontally, of an air cleaner having a horizontally arranged intake slot along one side thereof, said cleaner being mounted with the slot toward the engine, and opposite said side surface and a deflecting plate 105 positioned adjacent and co-extensive with the lower wall of said slot. 110

12. In an air cleaner, a separating chamber helical in cross section with its axis horizontal, formed by spaced overlapping walls, an air off-take pipe extending transversely of said chamber, said chamber having a dust exit opening along the lower portion thereof and a dust collecting chamber adjacent said opening. 115

13. In an air cleaner, a separating chamber substantially helical in cross section with its axis horizontal, formed by providing spaced overlapping walls upon one side of the chamber, an air off-take pipe extending 120 transversely of said chamber into the interior thereof, said chamber being provided with a dust exit along the lower portion thereof and a dust collecting chamber associated therewith. 125

14. In an air cleaner, a separating chamber substantially helical in cross-section whereby spaced over-lapping walls are provided above the upper side of the chamber; an air off-take pipe extending through said over-lapping walls; and a dust receptacle in communication with the chamber.
15. In an air cleaner, a separating chamber substantially helical in cross-section whereby spaced over-lapping walls are provided above the upper side of the chamber; an air off-take pipe extending through said over-lapping walls. In testimony whereof, I affix my signature.

CLYDE C. MANCHESTER.
